CLAIM

The ornamental design for a goalie hockey stick, as shown and described.

DESCRIPTION

FIG. 1 is a front side view of a goalie hockey stick showing my new design;

FIG. 2 is a rear side view thereof;

FIG. 3 is a left side view thereof;

FIG. 4 is a right side view thereof;

FIG. 5 is a top view thereof; and,

FIG. 6 is a bottom view thereof.

The broken away portion of the shaft is due to indeterminate length.
